UNITED STATES PATENT OFFICE.

ULYSSES G. LEE, OF CHICAGO, ILLINOIS, ASSIGNOR TO U. G. LEE & CO. INC., OF CHICAGO, ILLINOIS, A CORPORATION OF ILLINOIS.

MARINE WATER-CLOSET.

Application filed January 8, 1926. Serial No. 80,030.

My present invention relates to improvements in water closets designed especially for marine use, this application being a continuation in part of an application filed by me in the United States Patent Office on the 17th day of June, 1925, Serial No. 37,774.

One object of the invention is to provide a water closet provided with water supply and suction pumps located in separate compartments and operated by a single motor, both being located above the bottom of the bowl, whereby a certain amount of water will always be retained in the bowl.

Another object is to provide such an arrangement with the supply pump at the end of the drive shaft and the discharge pump located between the supply pump and motor.

I have also aimed to provide a construction in which the supply pump will act in conjunction with a suction chamber, normally closed to the entrance of sea water, but provided with an automatic suction-operated control valve.

Also I have aimed to provide a form of bowl having an integral platform base for support of the motor, pumps and associated parts, with convenient arrangements for water supply and sewage discharge.

A further object is to provide a construction in which the supply pump is always primed and ready to function properly.

The invention further aims to provide a construction, which, while embodying the above features, will be proof against the action or entry of water from outside of the boat.

Still another object is to provide a simplified construction capable of economical manufacture and ready assembly or repair.

With these and other objects in view, which will hereinafter appear, the invention comprises the novel features of construction and arrangement and combination of parts hereinafter described, and defined by the appended claims.

What I at present consider the preferred embodiment of my invention is illustrated in the accompanying drawings, in which:—

Figure 1 is a side elevation showing my improved water closet as applied to a vessel, a portion of the hull of which is shown conventionally.

Fig. 2 is a rear elevation partly broken away to show parts in section.

Fig. 3 is a section on line 2—2 of Fig. 2, and

Fig. 4 is a section on line 4—4 of Fig. 2, partly broken away.

Referring by reference characters to this drawing, the numeral 1 designates the closet bowl having the customary annular flushing conduit 1^a communicating with the bowl by the openings or water passages α . The base is formed with a rearwardly (left Fig. 1) projecting integral shelf portion 1^b which serves as a support for the flushing mechanism hereinafter described.

The bottom of the bowl is provided with a discharge portion, or pipe 1^c (preferably cast or formed integral therewith) which passes upward through the extension 1^b to one side of the center of the base so as to leave space for the supply and discharge pipes hereinafter described. The flushing mechanism comprises three main elements, to wit: a pump casing 2, a suction chamber 3 and a motor 4, all carried by a bed plate adapted to be bolted to the shelf formed by the rearward extension 1^b above referred to.

Bed plate 5 has a vertical passage 5^a to align respectively with the outlet of the bowl discharge 1^c and the suction pump intake (hereinafter described) and also horizontal ports or passages 5^b and 5^c for sea water supply and sewage discharge, these terminating in nipples or short pipe extensions, as shown in Figs. 1 and 3, for the usual lead pipe connections to the exterior of the hull of the vessel.

The pump casing 2 is divided by a partition 2^a, (Fig. 2) into two compartments 2^b and 2^c respectively, and the partition 2^a is preferably formed with a separately insertable and removable portion 2^d which may be in the form of a circular disc having a threaded periphery for screw connection with the opening in the partition wall 2^a.

The compartment 2^c has one side formed open and adapted to be closed by the juxtaposed wall of the suction chamber 3, which has a port 3^a near the lower end thereof communicating with the pump chamber 2^c. Within the pump chambers 2^b and 2^c are located the rotary suction and supply pumps 5^a and 6 respectively, which may be of any desired form, preferably of impeller or centrifugal type, as disc-like mem-

bers having curved or straight radial blades, the edges of which face the fluid admitting openings. The design of blades and shape of pump chambers may be of any approved or desired form, as will be obvious. The shaft 4^a of the motor 4 is connected by a universal joint of any approved type (shown conventionally at 7) to a pump shaft 8 which passes through a suitable stuffing box 9 in the wall of the suction pipe, and carries at or adjacent the intake of the pump 5^a paddles or the like 9^a designed to break up sewage before it is acted on by the pump, thereby preventing clogging of the latter. The inner wall of the pump chamber is also provided with projections *b* which cooperate with paddles 9^a in breaking up sewage.

Preferably the pump is formed with an integral sleeve or hub which also carries the aforesaid paddles 9^a.

The shaft 8 is projected through a central opening in partition disc 2^a and its free end carries the pump rotor 6.

In the upper part of the pump casing is a chamber 2^e which communicates with the pump chamber on the delivery side by a port provided with an upwardly opening check valve 10 which may be of the gravity type.

This chamber 2^e constitutes the upper end of a passage 10^a which connects with the passage 5^e in the base, hereinbefore referred to.

The delivery side (upper) of pump chamber 2^e is connected with the bowl conduit 1^a by a short pipe member 11 having one end bolted to the top of the pump casing in alignment with a delivery port therein (dotted lines Fig. 3) and the other end opening laterally and connected to the bowl as shown in Figs. 2 and 3, being held in place by tie bolt 11^a, the joints being suitably packed.

The suction casing 3 connects with the passage 5^b in the base and carries an inlet pipe or short tube 12 which may conveniently have a threaded connection with the suction casing, as shown in Fig. 2, and has its lower end formed as or provided with a valve seat to cooperate with a downwardly opening valve 13. The inlet pipe 12 is open at its upper end and the valve is provided with a stem or rod 13^a projecting upward through the stand pipe and connected at its upper end to a diaphragm 14 held in position by the dome-shaped cover 3^b of the suction casing 3.

A spring 13^b acting upwardly against the diaphragm tends to keep the valve closed, or a lever and weight may be provided to take the place of the spring.

Any suitable push button actuated switch mechanism preferably of the retarded type may be used for controlling the action of

the motor, as indicated conventionally at 15.

A casing 16 is provided for housing or enclosing the motor pump and associated mechanism, which casing may be used as the support for the seat and cover through hinge connections 17.

The pipe member 11 has a contracted portion as indicated at 11^x into which extends the end of a pipe 20 which is in communication at its opposite end with the intake of pump chamber 2^b. Preferably the pump chamber intake is provided with an offset portion shown in Fig. 4, and designated 2^x, into the upper wall of which is tapped a cylinder member 21 carrying a strainer 21^a, the pipe 20 being connected to the upper end of cylinder member 21 and the latter forming an extension of pipe 20 and a convenient means of connecting the latter and providing strainer carrying means. Pipe 20 extends into the restricted portion of pipe or conduit member 11 and has its end facing in the direction of the flow of water so that as the passage of the water is accelerated by the contraction, a suction effect on pipe 20 is produced.

From the foregoing description it is believed the construction and operation of my invention will be readily understood, but it may be briefly stated as follows:—

The pump 6, as will be readily observed, will be normally submerged, due to the fact that the top of the inlet pipe and the outlet port from the pump chamber 2^e are both above the pump and at this time (when the motor is at rest) the water level in the bowl will stand at the level indicated by the dotted line *x*.

If now the motor is started by operation of the push button, the pump 6 immediately creates suction in the suction chamber 3, which draws down on the diaphragm against the tension of spring 13^b and opens the valve 13, allowing sea water to flow in and be supplied to the bowl as long as the motor is operating.

At this time the suction pump 5^a will be inoperative, as water level *x* being below the level of the pump 5^a, the latter will not be submerged, and the first operation will be to raise the level in the bowl to say that indicated by dotted line *y*, or until the suction pump rotor 5^a is submerged, whereupon it will at once begin to function and withdraw the contents of the bowl and discharge it to the exterior of the vessel. The suction action of the water on pipe 20, hereinbefore referred to, causes air to be withdrawn from the pump chamber 2^b whereby water is free to flow into the suction pump chamber and prime the latter as soon as the bowl level is raised to level *y*. Suction pump 5^a is made of greater capacity than supply pump 6, as indicated by the extra width of blades 130

and larger port area, for example, so that the latter withdraws water from the bowl faster than it is supplied, dropping the water level to line α , whereupon air is withdrawn from the bowl. This results in the suction pump losing its prime until the water again rises, when liquid discharge from the bowl is resumed, this intermittent action continuing as long as the motor circuit is closed.

10 It will be observed that as soon as the ejection pump 5^a is primed and in operation, it produces a suction on pipe 20 which counteracts the suction on the upper end thereof, which results in a passage of water down-
15 ward through pipe 20, which has the effect of clearing the screen, and this occurs at every intermittent cycle.

When the motor stops and flow of water through member 11 ceases, a portion of the 20 water drains down through pipe 20 and as soon as conduit 11 is empty air is free to pass through pipe 20 to the eduction pump inlet and the water in the eduction pump casing drains back into the bowl to aid in 25 restoring the water level to that indicated at α .

After the motor stops, the water drains from the suction pump casing back into the bowl, restoring the level to line α , the parts 30 being restored to position for renewed operation, as above described.

When the motor is at rest, as the valves 10 and 13 are closed, entrance of sea water, due to wave or other causes, is prevented.

35 Having thus described my invention, what I claim is:—

1. In a marine water closet, a bowl having inlet and outlet passages, supply and eduction pumps in said passages, the eduction 40 pump having a greater capacity than the supply pump, means for operating said pumps simultaneously, and means for keeping the supply pump submerged in water while the eduction pump is allowed to drain 45 back into the bowl.

2. In a marine water closet, the combination with the bowl of a pump casing having a pair of adjacent pump chambers, water supply and sewage eduction connections 50 between the bowl and said chambers, centrifugal pump rotors located in said chambers, an operating shaft on which said rotors are mounted, said shaft extending through the sewage eduction chamber and into the water supply chamber, the rotor in said supply chamber being mounted on the end of the shaft.

3. In a marine water closet, a bowl having inlet and outlet passages, supply and eduction pumps in said passages, the eduction pump having a greater capacity than the supply pump, means for simultaneously operating said pumps, there being a suction chamber on the intake side of the supply pump, a normally closed outwardly open-

ing valve controlling the inlet of water to said suction chamber, and means whereby the suction created by said supply pump opens said valve.

4. In a marine water closet, the combination 70 with the bowl and water supply and sewage eduction passages of a pump casing having a pair of juxtaposed pump chambers included in said passages, a suction chamber included in said water supply passage, said suction chamber having an inlet pipe extending above the pump intake, and a valve governing the admission of water to said inlet pipe, and automatic suction controlled means for opening said valve to admit water. 75

5. In a marine water closet, the combination with the bowl and water supply and sewage eduction passages, of a sewage eduction pump cooperating with the eduction passage, said water supply passage including a pump chamber and an adjacent suction chamber, communicating at its lower end with said pump chamber, a bladed rotor in said pump chamber facing said communication, an inlet pipe in said chamber having 80 its lower end communicating with the water supply and its upper end opening into the suction chamber above the communication to the pump chamber, and a suction controlled valve governing the admission of water to 85 said stand pipe.

6. A marine water closet according to claim 5, in which the valve has a stem extending through the inlet pipe connected at its upper end to a yieldable diaphragm. 100

7. In a marine water closet, the combination with the bowl and water supply thereto of a pump casing having sewage eduction pipe connections thereto, a bladed rotor in said casing, a shaft on which said rotor 105 is mounted, said casing having an intake opening, and projections carried by said shaft in said intake opening, for breaking up sewage.

8. In a marine water closet, the combination with the bowl and water supply thereto of a pump casing having sewage eduction pipe connections thereto, a bladed rotor in said casing, a shaft on which said rotor is mounted, said casing having an intake opening, and projections carried by said shaft in said intake opening, the wall of said intake opening having inwardly extending 115 projections cooperating with the projections on the shaft, for breaking up sewage. 120

9. In a marine water closet, a bowl having a rim flushing channel, a rotary supply pump connected to supply water to said rim, an eduction pump connected to withdraw the bowl contents, both said pumps being 125 located above the bottom of the bowl, means for keeping the supply pump primed, and means for admitting air to the eduction pump chamber when the pumps are at rest.

10. In a marine water closet, a bowl hav-

ing a rim flushing channel, a rotary supply pump connected to supply water to said rim, an eduction pump connected to withdraw the bowl contents, both said pumps being located above the bottom of the bowl outlet, and said eduction pump having a greater capacity than the supply pump, means for operating said pumps in unison, means for keeping the supply pump constantly primed, and a pipe leading from the intake of the eduction pump to the connection between the supply pump and the rim channel.

11. In a marine water closet, a bowl having a rim flushing channel, a rotary supply pump connected to supply water to said rim, an eduction pump connected to withdraw the bowl contents, both said pumps being located above the bottom of the bowl outlet, and said eduction pump having a greater capacity than the supply pump, means for operating said pumps in unison, means for keeping the supply pump constantly primed, and a pipe leading from the intake of the eduction pump to the con-

nection between the supply pump and the rim channel, said connection having a restricted portion for accelerating the flow and said pipe extending into said restricted portion and having its open end facing in the direction of water flow.

12. In a marine water closet, a bowl having a rim flushing channel, a rotary supply pump connected to supply water to said rim, an eduction pump connected to withdraw the bowl contents, both said pumps being located above the bottom of the bowl, and said eduction pump having a greater capacity than the supply pump, means for operating said pumps in unison, means for keeping the supply pump constantly primed, and a pipe leading from the intake of the eduction pump to the connection between the supply pump and the rim channel, said pipe having a strainer embodied in its connection with the eduction pump.

In testimony whereof I affix my signature.

ULYSSES G. LEE.
